UNITED STATES PATENT OFFICE

151,330

DESIGN FOR AN AUTOMOBILE HOOD
LOUVER

Neil J. De Sanders, Dallas, Tex.

Application October 2, 1947, Serial No. 141,719

Term of patent 3½ years

(Cl. D14—18)

To all whom it may concern:

Be it known that I, Neil J. De Sanders, a citizen of the United States of America, residing at Dallas, in the county of Dallas and State of Texas, have invented a new, original, and ornamental Design for Automobile Hood Louvers, of which the following is a specification, reference being had to the accompanying drawing, forming a part thereof.

Fig. 1 is a front elevational view of an automobile hood louver, showing my new design,

Fig. 2 is a rear elevational view of the louver,

Fig. 3 is a top plan view of the louver,

Fig. 4 is a view in elevation of the underside of the louver,

Fig. 5 is an end elevational view of the forward end of the louver, and

Fig. 6 is an end elevational view of the rearward end of the louver.

I claim:

The ornamental design for an automobile hood louver, as shown.

NEIL J. DE SANDERS.
